UNITED STATES PATENT OFFICE.

FRANZ X. WAGNER, OF NEW YORK, N. Y., ASSIGNOR TO THE WAGNER TYPEWRITER COMPANY, OF SAME PLACE.

TYPE-WRITING MACHINE.

SPECIFICATION forming part of Letters Patent No. 660,231, dated October 23, 1900.

Application filed January 25, 1900. Serial No. 2,737. (No model.)

To all whom it may concern:

Be it known that I, FRANZ X. WAGNER, a citizen of the United States, residing in the borough of Manhattan, city, county, and State of New York, have invented certain new and useful Improvements in Type-Writing Machines, of which the following is a full, clear, and exact description.

My invention relates to type-writing machines, and more particularly to mechanism for writing accent-marks with facility.

The object of the invention is to provide a simple and efficient mechanism of the character described and preferably one which is in the nature of an attachment that is adapted to be applied to coöperate with any of the various type-carriers in the machine.

To this end my invention consists in the novel arrangement and combination of parts to be hereinafter described and claimed.

In the accompanying drawings, Figure 1 represents a transverse vertical sectional view of a machine embodying my invention, the section being taken centrally through the machine. Fig. 2 is a detail plan view of a portion of the mechanism to be hereinafter described. Fig. 3 is a side view of the same with parts broken away for the purpose of better illustration.

30 In illustrating my invention I have shown it applied to the well-known "Underwood" type-writing machine, to which said invention is specially adapted, though obviously the invention may be applied to other type-writing machines, and the necessary changes in detail of construction for the adaptation of the invention to other machines will readily occur to those skilled in the art to which this invention appertains.

40 In the drawings, 1 designates the framing of the machine, in which is mounted a segmental plate 2. This plate 2 carries a pivot 3, upon which the type-carriers or type-bars 4 are pivotally mounted. Each of the type-carriers or type-bars 4 is connected to a link 5, pivoted to the framing of the machine, as indicated at 6, and pivotally united to a key-lever 7, as indicated at 8. The key-levers 7 are each provided with the usual finger-key 9 and are pivoted to the framing of the machine, as indicated at 10. Each of the type-

bars or carriers 4 is provided with a nose 11, which is adapted to abut against a universal bar 12 in the movement of the type-bar to the printing-point and to cause a rearward movement to be given to the universal bar. The carriage-feed mechanism or escapement is connected to this universal bar, and each complete movement thereof causes the platen-carriage 13 to be fed one space in the usual manner. In the present instance this feed mechanism comprises a table 14, which is connected to the universal bar at one end and to the crank-arms 15 at the other. The table carries a plurality of feed-dogs 16, which successively engage a rack 17, carried by the carriage, so as to effect a feed of the carriage at each complete lateral movement of the feed-dogs to and from the initial position. The arms 15, hereinbefore referred to, are rigidly connected to a rock-shaft 18, which has an arm 19 secured thereto. This arm 19 is provided with an extension 20, against which a crank-arm 21 is adapted to bear. This crank-arm 21 is fixed upon a rock-shaft 22, that is adapted to oscillate in the framing of the machine and to which spacing-levers 23 are connected. These spacing-levers 23 have the usual spacing-key 24 connected to the outer ends thereof. The arm 19, hereinbefore referred to, is provided with a slot 25, into which a pin 26 projects. This pin 26 is carried upon a crank-arm 27, that is rigidly connected to a rock-shaft 28. This rock-shaft 28 is provided with arms 29, to each of which is pivoted a feed-pawl 30, that coöperates with a ratchet-wheel 31. Each of the ratchet-wheels 31 is connected up in a suitable manner to the ribbon-spools upon which the ribbon 32 is carried.

So much of the mechanism as has thus far been described constitutes mechanism of the well-known Underwood type-writing machine, and I will now proceed to describe the mechanism which coöperates therewith to carry out the purposes of this invention.

Upon the framing 1 of the machine is adapted to be secured a carrier *a*, which may be secured in place by suitable means, such as the screw *b*. This carrier *a* may be secured to any portion of the framing in the machine adjacent to any of the key-levers in

the machine. In the present instance I have illustrated this carrier as connected to the framing of the machine immediately in the rear of one of the key-levers. Pivoted to the 5 carrier *a* is what I term a "locking-dog" *c*, as indicated at *d*. The movement of the locking-dog around its pivot is limited by the under face of the locking-dog abutting against the top *e* of the locking-dog carrier *a*. The 10 locking-dog *c* is normally maintained in the elevated position by a spring *f*, which in the present instance is located within the dog-carrier *a* and abuts against the lower face of the locking-dog. Projecting through an aperture *g* in the locking-dog is a rod *h*, which 15 is adapted to be connected to any of the key-levers which is to constitute what I term a "blank" key in the machine. I term this key a "blank" key, because in the operation 20 thereof no feed of the carriage is effected, as will hereinafter more fully appear. Surrounding the rod *h* is a coiled spring *i*, one end of which bears against the upper face of the locking-dog *c* and the other end of which 25 bears against an adjusting screw or screws *j* by means of which latter the tension of the spring can be adjusted. In the normal position of the parts (represented in Fig. 1 of the drawings) there is practically no tension exerted by the spring *i* upon the locking-dog; 30 but when the blank key is depressed the spring *i* is immediately placed under tension and is sufficient to overcome the tension of the spring *f*, so as to depress the locking-dog 35 when it is free to be depressed. The free end of the locking-dog is adapted to cooperate with a locking-abutment *k*, which locking-abutment is carried upon the rock-shaft 28 and is provided at the upper end thereof 40 with a notch *l*. In the normal or unlocked position (represented in Fig. 1 of the drawings) the locking-dog is maintained above or out of the path of the locking-abutment by means of the spring *f*. 45 Having described a construction embodying my invention, I will now proceed to describe the operation thereof.

A depression of the blank key will first cause the universal bar to be shifted by the 50 contact of the nose 11 of a type-carrier therewith. Motion transmitted in this manner to the universal bar will cause the feed mechanism to be given a lateral movement in the direction of the arrow *x*, which movement in itself, however, is insufficient to cause the carriage to be fed, it being necessary for the feed mechanism to return to the normal position before a feeding of the carriage is effected. This movement of the feed-dog is 55 transmitted through the arms 15 to the rock-shaft 18 and from the rock-shaft 18 to the arm 19, which will cause the rock-shaft 28 to be vibrated, causing the locking-abutment to be moved in the direction of the arrow *y* a 60 sufficient distance to bring the notch *l* beneath the free end of the locking-dog. The depression of the blank key places the locking-dog

under the tension of the spring *i*, and as soon as the recess or notch *l* is brought into position beneath the locking-dog it will be forced 70 by the spring *i* into the notch, and the nose *m* of the locking-abutment will contact therewith and will prevent the locking-abutment from returning to the normal position, thereby preventing the entire carriage-feed mechanism from resuming the normal position, and consequently preventing a feed of the carriage. It will be observed that this same movement of all parts of the spacing mechanism is effected when the spacing-key 24 is depressed. The depression of the spacing-key causes the arm 21 to be elevated, thereby shifting the parts of the carriage-feed mechanism in the manner described by reason of the coöperation of the arm 21 with the ex- 80 tension 20. It should be understood at this point that the so-called "blank" key is provided with the desired accent-mark and that a depression of the key will cause an imprint of the accent-mark at the printing-point. The 85 positioning of the accent-mark upon its type-bar will of course depend upon the character of the mark and the position it is to occupy with relation to the letter to be written. The depression of the blank key having made 90 the imprint of the accent-mark upon the paper adjacent to the letter to be written and having automatically locked the carriage-feed mechanism out of operation, the desired letter which is to coöperate with the accent-mark is then written. A movement or depression of the writing-key, which causes an 95 imprint of the letter, will produce a slight movement of the feed mechanism in the direction of the arrow *x* in the manner hereinbefore described, and this movement will cause the locking-dog to be freed from the nose *m* of the locking-abutment, and the locking-dog 100 will be forced into the elevated position by the spring *f*, because of the fact that the spring *i* at this time is not under tension and affords no resistance to the upward movement of the locking-dog. It will thus be seen 105 that a movement of the blank key causes an imprint of the accent-mark to be made and simultaneously locks the carriage-feed mechanism out of operation and that a depression of any of the writing-keys will cause an imprint to be made in the same space that the accent-mark has been imprinted. 110 At the same time an automatic release of the feed mechanism will be effected, so that the operator may proceed with the writing in the usual manner. It will likewise be observed 115 that the locking of the feed mechanism out of operation during the imprint of the accent-mark and the character which co-operates therewith and the releasing of the feed mechanism immediately after such character is written is effected automatically. 120 125 130

While I have described with considerable detail a construction embodying my invention, I am aware that various changes may be made without departing from the spirit of my

invention. Thus while I have shown the locking mechanism so constructed as to be operated in part by the mechanism which directly effects the feed of the ribbon, but which is nevertheless controlled and operated by the feeding mechanism, it is obvious that this movement of the parts may be effected from any portion of the carriage-feed mechanism.

Having described my invention, what I claim, and desire to secure by Letters Patent, is—

1. In a device of the character specified, the combination of a carriage, feed mechanism for effecting a movement of the carriage in the direction of its feed, a "blank" key and means controlled by the operation of said "blank" key for automatically locking the feed mechanism out of operation and for maintaining the carriage against movement in the direction of its feed when the "blank" key is operated.

2. In a device of the character specified, the combination of type-carriers, keys for operating said type-carriers, a carriage, feed mechanism for said carriage, a "blank" key and means controlled by the operation of said "blank" key for automatically locking the feed mechanism out of operation when the "blank" key is operated, the feed mechanism and locking means coöperating to effect a release of the locking means when any of the keys of the type-carriers are operated.

3. In a device of the character specified, the combination of type-carriers, keys for operating said type-carriers, a carriage, feed mechanism for said carriage, a spacing key for operating said spacing mechanism, a "blank" key, means controlled by the operation of said "blank" key for automatically locking the feed mechanism out of operation when the "blank" key is operated and mechanism for automatically effecting the release of the locking means by a depression of any of the keys of the type-carriers or by the depression of the spacing-key.

4. In a type-writing machine, the combination of a detachable locking-dog support, a locking-dog carried thereby, means for operatively connecting said dog to a writing-key, and a locking-abutment coöperating with the locking-dog and adapted to be moved at each operation of the finger or spacing key.

5. In a type-writing machine, the combination of spacing mechanism, a movable spring-

pressed locking-dog, means for operatively connecting said dog to a writing-key, and a locking-abutment coöperating with the locking-dog, said locking-abutment being adapted to be operatively connected to the spacing mechanism and adapted to be moved at each operation of said spacing mechanism.

6. In a type-writing machine, the combination of spacing mechanism, a movable spring-pressed locking-dog, yielding means for operatively connecting said dog to a writing-key, the tension of said yielding means being sufficient to overcome the tension of the spring of the locking-dog, and a locking-abutment coöperating with the locking-dog, said locking-abutment being adapted to be operatively connected to the spacing mechanism and adapted to be moved at each operation of said spacing mechanism.

7. In a type-writing machine, the combination of a movable spring-pressed locking-dog, a spring-pressed connection between said locking-dog and a writing-key, a locking-abutment with which said locking-dog coöperates, means for moving the locking-abutment at each operation of a writing or spacing key, and means carried by the locking-abutment to retain the locking-dog against movement.

8. The combination of a feed-dog, a rack, means for moving one of said elements laterally with relation to the other, a plurality of writing-keys and locking means operatively connected to one of said writing-keys for automatically locking the movable feed element against movement when the key to which the locking means are connected is operated.

9. The combination of a feed-dog and rack, means for moving one of said elements laterally with relation to the other, a plurality of writing-keys, a spacing-key, locking means operatively connected to one of said writing-keys for automatically locking the movable feed elements against movement in one direction when the key to which the locking means are connected is operated and means for automatically releasing said locking means upon the operation of any of the other keys.
